UNITED STATES PATENT OFFICE.

RUDOLPH FUCHS, OF STATEN ISLAND, NEW YORK, AND GEORGE B. BEIDERHASE, OF JERSEY CITY, NEW JERSEY.

DESIGN FOR A BRUSH OR MIRROR BACK.

SPECIFICATION forming part of Design No. 21,071, dated September 29, 1891.

Application filed August 18, 1891. Serial No. 403,057. Term of patent 3½ years.

To all whom it may concern:

Be it known that we, RUDOLPH FUCHS, a citizen of the United States, residing at Staten Island, county of Richmond, State of New York, and GEORGE B. BEIDERHASE, a citizen of the United States, residing at Jersey City, in the county of Hudson and State of New Jersey, have invented and produced a new and original Design for Brushes, Mirrors, or other Toilet Articles; and we do hereby declare the following to be a full, clear, and exact description of the same, reference being had to the accompanying drawing, forming a part thereof.

The design consists of a brush or mirror back or back of other like article, having ornamentation upon it comprising conventional figures *a a*, having the general contour of crescents, the concave sides whereof are ornamented with inwardly-projecting parts *b* and the outer or convex surfaces whereof are ornamented with conventional leaf-shaped figures *c*, the spaces between the figures *c* being supplied with conventional feather-like ornamentation *d*. The two principal crescent-shaped figures are placed opposite one another, so as to leave a plain surface *e* between them and between the horns of the crescent-shaped parts, and adjacent to the edges of the brush-back are placed other conventional figures *f f*, and a border *g*, of irregular design and composed of variously-shaped figures, surrounds the brush-back. Upon the back

of the handle other crescent-shaped figures *h h* appear, designed to coincide with the general design or style of the crescent-shaped figures upon the back of the body of the toilet article.

Those parts of the crescent-shaped figures, both upon the back of the brush proper and upon the back of the handle, which are in boldest relief are preferably smoothed or burnished. The other parts of the design that are sunken or in lower relief may be roughened or stippled.

The leading features of our design consist in the crescent-shaped figures having internal and external ornamentation, so arranged upon the back of the brush in conjunction with the other features of the design as that an open or plain surface shall be left at or near the central portion of the brush-back, together with the ornamented crescent-shaped figures upon the handle of the brush.

We claim—

The design for backs of brushes, hand-mirrors, and other toilet articles, substantially as herein shown and described.

In testimony whereof we affix our signatures in the presence of two witnesses.

R. FUCHS.
GEO. B. BEIDERHASE.
